UNITED STATES PATENT OFFICE.

NILS H. ANDERSON, OF EAST HAMPTON, CONNECTICUT, ASSIGNOR OF ONE-HALF TO
WILLIAM A. LORENZ, OF HARTFORD, CONNECTICUT.

NOISELESS TYPE-WRITER PLATEN.

1,235,756.

Specification of Letters Patent. Patented Aug. 7, 1917.

Application filed September 9, 1914, Serial No. 360,380. Renewed December 30, 1916. Serial No. 139,928.

To all whom it may concern:

Be it known that I, NILS H. ANDERSON, a citizen of the United States, and resident of East Hampton, in the county of Middlesex and State of Connecticut, have invented certain new and useful Improvements in Noiseless Type-Writer Platens, of which the following is a specification.

My present invention relates to new and 10 useful improvements in writing machine platens and particularly to what are known as noiseless platens.

The primary object of the invention is to produce a noiseless platen for machines of 15 the above class which will be simple and inexpensive to manufacture and which includes a metal tube or cylinder of novel construction having efficient noise absorbing qualities as will later be more fully explained.

With the above and other minor objects in view my invention resides and consists in the novel construction and arrangement of parts shown upon the accompanying sheet of drawings forming a part of this specification, 25 upon which similar characters of reference denote like or corresponding parts throughout the several figures and of which,

Figure 1 shows a longitudinal sectional elevation of my present novel form of noise- 30 less typewriter platen.

Fig. 2 is an end view of the same.

Fig. 3 is a cross section taken on line 3—3 of Fig. 1 and

Fig. 4 is a detail end view of my novel 35 form of sheet metal tube forming the core of the platen.

As will be noted the platen is made up of several internal collars that are located within a special form of spirally wound 40 sheet metal tube or core and which is so constructed and arranged as to retard and absorb the sounds caused by the striking of the keys upon the surface of the platen.

This tube is formed the full length of the 45 platen and over its outer surface is placed a hard rubber covering against which the type of the writing machine operates. The platen as thus formed is not only noiseless, but is light in weight besides being durable and 50 simple to manufacture and assemble.

Referring in detail to the characters of reference marked upon the drawings, 5 represents the shaft upon which the platen is mounted, 6 end caps having hubs through 55 which set screws 7 are seated to engage the

shaft and secure the platen thereto. Screws 8 serve to secure the end caps to the end collars 9. Insulating washers 10 are seated around the head of the screws and in recesses of the end caps and serve to insulate 60 the connection between the said end caps and the screws 8. An insulating washer 11 such as felt or rubber is also preferably arranged under the cap and between it and the collars and metal tube. In addition to the end collar 9 I preferably employ a centrally arranged collar 12 which serves to support the intermediate portion of the tube 13. These collars 9 and 12 are preferably made of wood and are each provided with a large central 65 opening 14 therethrough for the introduction of the supporting shaft.

The core, as before stated, is made of sheet metal as for instance sheet steel and is rolled to form a tube of the required diameter as shown in Fig. 4 and which when completed will represent several windings of the metal. This tube is held in shape by securing the outer longitudinal edge portion 15 of the metal sheet to the outer surface of 70 the outer cylindrical body, as by means of solder indicated by 16 in Figs. 3 and 4. The securing of these portions of the tube together in this manner insures the formation of a rigid tube of a uniform outer diameter and whose peripheral surface is 75 smooth and finished to receive the relatively hard rubber jacket or cover 17 that forms the working surface of the platen. The inner edge portion 18 of this sheet metal core 80 is left free and unsecured to the main outer shell, except so far as it may frictionally engage the inner wall of the outer winding as by reason of the spring tendency in the metal to unwind. The result of this inner 85 and loosely wound portion of the tube is to effectively absorb the sound waves produced by the operation of the type.

A tube formed in this way obviously does not have the sound carrying properties that 90 a solid or single wound tube would have and thus is more efficient for a core for a noise reducing platen.

The collars before mentioned may be held in position by friction or preferably by 95 means of small nails as indicated by 19 in Fig. 1 and which may be driven in through both the outer rubber covering 17 and the metal tube and into the collars.

Having thus described my invention what 100

I claim and desire to secure by Letters Patent is:—

1. A typewriter platen, comprising in part a core formed of sheet metal and rolled to form a tube of a plurality of thicknesses and whose outer longitudinal edge portion is secured to the adjacent peripheral surface of the tube.
2. A noiseless typewriter platen, comprising a core formed of sheet metal rolled to form a tube of a plurality of thicknesses and whose outer longitudinal edge portion is secured to the adjacent inner surface of the roll, and whose inner windings are disposed against the inner wall of the tube and whose inner edge portion is left free.
3. A typewriter platen, comprising in part a metal core comprising a rigid tube and a layer of sheet metal rolled to form an inner flexible tube of a plurality of thicknesses and whose outer longitudinal edge portion is secured to the core.
4. A typewriter platen, comprising in part a metal core comprising a rigid tube and a layer of sheet metal rolled to form an inner flexible tube of a plurality of thicknesses and whose outer longitudinal edge portion is secured to the core, a collar within the tube, end caps and a suitable covering for the platen.
5. A core for a typewriter platen, com-

prising a rigid metal tube and a plurality of thicknesses of sheet metal loosely wound therein and one of whose longitudinal edges is secured to the inside of the tube and whose other edge portion is left free.

6. A typewriting platen including in part a rigid tube and a plurality of windings of sheet metal contained therein and whose tendency is to expand and hug the inner wall 40 of the tube and whose inner edge portion is left free.

7. A typewriter platen including in part a rigid tube and a plurality of windings of sheet metal secured within the tube and 45 whose inner edge portion is left free and unsecured.

8. A typewriter platen consisting of a composition cylinder with a continuous outer working surface, a tubular core reinforcing the cylinder, said core being formed of sheet metal rolled into a cylinder having 50 walls of a plural number of layers, and heads at the ends of the core.

Signed at East Hampton in the county of 55 Middlesex and State of Connecticut this 2nd day of September A. D., 1914.
